FIG. 6 -

UNITED STATES PATENT OFFICE.

OLE J. TRETSVEN, OF FREDERIC, WISCONSIN.

COMBINATION TABLE AND IRONING BOARD.

1,402,689.

Specification of Letters Patent.

Patented Jan. 3, 1922.

Application filed May 9, 1921. Serial No. 468,012.

To all whom it may concern:

Be it known that I, OLE J. TRETSVEN, a citizen of the United States, residing at Frederic, in the county of Polk and State of Wisconsin, have invented certain new and useful Improvements in Combination Tables and Ironing Boards, of which the following is a specification.

This invention relates to kitchen furniture and the main object is to provide an efficient, practical and novel construction of combination table and ironing board, in which the latter is slidably mounted and secured in the former. Further objects will 10 be disclosed in the course of the following specification and are illustrated in the accompanying drawing, in which;

Fig. 1 is a side elevation of a table and an ironing board secured thereto, embodying 20 my invention, a portion of the table being broken away.

Fig. 2 is a sectional view on the line 2—2 in Fig. 1.

Fig. 3 is a sectional view on the line 3—3 25 in Fig. 1.

Fig. 4 is an enlarged section on the line 4—4 in Fig. 2.

Fig. 5 is an enlarged section on the line 5—5 in Fig. 1.

Fig. 6 is an enlarged section on the line 6—6 in Fig. 1.

Referring to the drawing by reference numerals, 7 designates the legs of a table having a top 8, side boards 9 and an end 35 board 11. An ironing board 11^a is slidably mounted in a slot 12 in the end board 11. The inner end of the board is provided with a transverse brace 13 whose ends slidably engage between two strips 14 fixed on the 40 inner sides of the side boards 9. The lower strips 14 are provided with notches 15 into which the ends of the brace 13 may fall when the board is extended its full length. Two small catches or levers 16 are pivotally 45 secured under the end of the table top 8 and are adapted to be turned under and squeezed in between the table top and the ironing board when the latter has been fully extended and the brace 13 has dropped into the notches 15, thus firmly securing the inner end of the board in a rigid manner to the table.

The outer end of the board 11^a is preferably supported on a leg 17 which is pivotally secured to it so as to swing up against it, 55 and which slides in a slot 18 in the end board when closed. A guiding strip 19 is secured centrally on the leg 17, and when the leg is folded up, this strip continues in two strips 20 secured in similar central position under the board 11^a. The strips 19, 20 60 guide in a small notch 21 in the end board 11 and hold the board 11^a in central position in its larger notch 12 so that padding which may be secured to the board will not catch 65 on the end board 11 when the ironing board is being pushed in or extended. A strip 22 is secured at its ends to the end boards of the table and is arranged so that the strips 19, 20 will slide on and be supported by it when 70 the ironing board is pushed in.

It is understood that suitable modifications may be made in the form and structure of this device if such modifications come within the spirit and scope of the appended 75 claims.

Having now therefore fully shown and described my invention, what I claim to be new and desire to protect is:

1. In combination with a table, an ironing board slidably mounted in the end board thereof, a transverse brace fixed on the inner end of the ironing board, upper and lower strips arranged at the sides of the table for guiding said brace, said lower strips having 80 notches adapted to receive the brace when the board is extended, and finger catches adapted to engage between the ironing board and the top of the table when said board is 85 fully extended, substantially as described. 90

2. In combination with a table, an ironing board slidably mounted in a slot in the end board of the table, said slot being wider than the widest part of the ironing board, a leg hingedly secured to the ironing board so as 95 to fold up against it, a strip fixed longitudinally on the leg, strips on the ironing board arranged in alignment with the leg strip when the leg is folded up, all of said strips being adapted to slide in a notch in said end 100 board and keep the ironing board in central position in the slot it engages.

3. In combination with a table, an ironing board slidably mounted in the end board

of the table, a leg hingedly secured to the ironing board and adapted to fold up thereagainst, said end board of the table having a slot adapted to receive said leg, a supporting strip arranged longitudinally and centrally under the table for slidably supporting said leg when the ironing board is

pushed into the table, and means for guiding the ironing board when thus sliding it into the table.

In testimony whereof I affix my signature.

10

OLE J. TRETSVEN.
